UNITED STATES PATENT OFFICE

LEO F. NOIROT, OTTO G. NOIROT, AND GEORGE C. RUPERT, OF PEORIA, ILLINOIS

RADIOANTENNA

Application filed October 21, 1927. Serial No. 227,805.

This invention pertains to radio antennæ.

An object is the provision of an antenna of a restricted form wound substantially in the form of a ball that is portable and which includes a novel arrangement of mounting of the wire serving to receive the radio waves.

Another object is to provide a ball form of antenna wherein the wire for receiving the radio waves is wound upon a support but thoroughly insulated from such support.

Still another object is to provide a supporting structure upon which the antenna wire is wound spirally, the several convolutions of the wire being insulated from one another and from such structure.

In addition, the invention relates to certain details of construction and arrangements of parts to be brought out herein aided by the accompanying drawing in which:

20 Figure 1 is an elevation of my improved antenna in a preferred form.

Figure 2 is a plan of part of the same as seen from its under or lower side.

Figure 3 is a vertical section of part of the 25 invention showing structural details, and

Figure 4 shows part of a supporting member of the antenna in perspective.

The antenna of our invention is substantially ball-shaped and to the end that it may be preferably so constructed we provide a series of strips 1 preferably of metal for the sake of strength and rigidity, which are bent into substantially semicircular form. As shown in Figure 2 these strips diverge from a common point, their ends being secured in suitable manner as by rivets 2, for example, to plates 3 at diametrically opposite positions in the completed ball, said plates being shown in Figure 1 as to their positions, being spaced apart about as shown. At spaced intervals the strips 1 are furnished with ears or lugs 4 struck up therefrom, Figure 4, these being for a purpose to appear.

Preferably in order to brace the structure 45 and hold it in shape a rod 5 is erected within it, its ends being screw threaded and extended through the plates 3 receiving nuts 6 at each side of each of the latter. The rod 5 is insulated from the plates 3 by interposing 50 insulating material 7 between the parts as

illustrated in Figure 3. The rod may be mounted upon a suitable support such as a pole or building, not shown, or as shown in said Figure 3 a ring 8 may be secured under one of the nuts 6 by which to suspend the structure from any support, not shown.

Upon the radial strips 1 is now placed a suitable conductor 8' for receiving the radio waves, said conductor being wound spirally beginning at a point near one of the plates 3, for example, lodging the windings against or behind the ears 4 of the strips 1, there being insulating portions 9, preferably tubes of glass, interposed between the conductor and the said strips 1, the conductor being in fact threaded through said tubes. The conductor is thus prevented having contact with the strips 1 preventing "shorting" and perhaps grounding under certain conditions. One terminal of the conductor is electrically connected to a binding screw 10 attached to and insulated from the structure, the "lead in" of the radio set, neither of which is shown, being likewise attached to said binding screw.

Glass has been found to be the best type of 75 insulation for protecting the conductor 8' since moisture cannot permeate it and destroy the effectiveness of the device.

We claim:

1. An antenna structure including a series 80 of strips circularly curved in the direction of their lengths, a member at each end of the strips to which the same are secured in radiating spaced relation, a series of ears struck up from the strips at their outer sides along the lengths thereof in spaced relation, and a winding of wire mounted upon the structure lodged against said ears, the windings of said wire being insulated from said strips and from each other.

2. An antenna structure including a series 85 of strips circularly curved throughout their lengths, a member at each end of the strips to which the same are secured in rigid radiating spaced relation, a series of ears struck up from the strips at their outer sides along the same in spaced relation, a winding of wire mounted upon the structure lodged against said ears, an insulating portion interposed 95 between the windings and said strips, and a 100

strut spacing apart the members to which the said strips are attached and maintaining the structure rigid.

3. An antenna ball comprising a series of strips circularly curved, spaced apart and secured relatively forming a ball-like structure, a member spacing apart and connecting the strips centrally of the structure, said strips each having ears struck up therefrom along its longitudinal line and extending from the outer surface thereof, and a wire spirally wound upon the strips behind the ears thereof in a single given direction, the same being insulated from the strips, the convolutions of the wire being insulated from each other.

In testimony whereof we affix our signatures.

LEO F. NOIROT.
OTTO G. NOIROT.
GEORGE C. RUPERT.
